ELECTRIC LIGHT FLASHER

Silas G. Ramsey, University City, and Edwin S. Zacharias, Clayton, Mo.

Application October 16, 1931. Serial No. 569,237

3 Claims. (Cl. 200—122)

This invention relates to an electric light flasher; and has particular reference to devices for simultaneously lighting and simultaneously extinguishing the light of a number of electric lamps.

This invention relates to a modification of an invention described and claimed in our application filed October 16, 1931, Serial No. 569,236.

An object of the invention is to provide an improved and simplified device arranged to operate automatically as an incident to the closing of a switch to an electric lamp with which a number of additional lamps are in parallel circuit, in order to control the electric circuit effectively to light all of the lamps simultaneously and to extinguish the light of all of the lamps simultaneously.

Another object of the invention is to provide an improved electric lamp socket containing a device operating to interrupt the effective flow of electrical energy in such a way as to light and to extinguish the light of the lamp alternately and at predetermined intervals.

Other objects of the invention will appear from the following description, reference being made to the accompanying drawing, in which—

Fig. 1 is a top plan view of two electric lamp sockets connected with an electric circuit in accordance with the principles of the present invention.

Fig. 2 is a sectional view on the line 2—2 of Fig. 1.

Fig. 3 is an inverted plan view of the principal socket.

Fig. 4 is a sectional view on the line 4—4 of Fig. 1.

Fig. 5 is a diagrammatic view of the electric circuit.

The controlling socket of the invention comprises an electrically non-conductive body including a socket portion 1 and a base 2. A metallic sleeve 3 is secured within the socket 1 and is in electrical communication with a metallic arm 4 projecting laterally therefrom and secured to the base 2 by a metallic screw fastener 5. A wire 6 of the electrical circuit is attached to the arm 4 by the fastener screw 5.

The other circuit wire 7 is attached by a fastener screw 8 to a metallic strip 9. The screw 8 is also utilized to secure the strip 9 to the base 2 of the socket.

A bar 10 comprising two strips of metal secured together in superimposed relationship and having different coefficients of expansion and contraction when heated and cooled has its inner

end embedded in the base and attached to the electrical conductor member 11. The conductor member 11 is rigid in the base of the socket and extends upwardly into the socket in position to be engaged by the point 12 of the electric lamp 13. It is known that one end of the filament 13a of the lamp 13 is in electrical communication with the point 12 and that the other end of said filament is in electrical communication with the metallic band 14 attached to the bulb of the lamp and threaded so that the same may be screwed into and out of the sleeve 3 with which the wire 6 is in electrical communication.

A coil of wire 15 is wound around an insulation sleeve 16 mounted on the bar 10, the inner end of said wire being in electrical contact either with the bar 10 or the electrical conductor 11, as may be desired. A wire 17 connects the wire 15 with a fastener screw device 18, whereby said wire 17 is held in electrical communication with the strip 9. A contact member 19 attached to the bar 10 is movable, by bending said bar 10, into and out of contact with the cooperating contact member 20 attached to the inner end of the fastener screw device 18.

The socket 21 is of conventional construction, being designed and arranged to support a lamp 22 in the manner shown, in which the metallic band 23 on said lamp is screwed in the threaded sleeve 24 mounted in said socket 21 and in electrical communication with the metallic arm 25 to which one end of a wire 26 is secured by a binding screw 27. The opposite end of the wire 26 is attached by a screw 28 to a metallic strip 29 which is embedded in the base 2 of the primary socket and is in electrical contact with the electrical conductor member 11.

It is known that one end of the filament of the lamp 22 is in electrical communication with the band 23 and that the other end of said filament is in electrical communication with the point 30 which is designed and adapted to engage a contact member 31 that is in electrical communication with an electric conductor 32 secured in the base of the socket 21. A strip 33 forms electrical communication from the conductor member 32 and is secured to one end of a wire 34 by a binder screw 35. The opposite end of the wire 34 is engaged with the screw 5 and the arm 4.

When the electric circuit to the wires 6 and 7 is closed, the electrical energy passes through the wire 7, the strip 9, wire 17, wire 15, conductor member 11, point 12, filament of the lamp 13a, and thence to the wire 6, or vice versa. The resistance obtained by the wire 15 prevents the

next; electrical communication with said contact member and out of electrical communication with said sleeve, a contact member attached to said socket for cooperation with said switch member adapted to be in permanent communication with the other circuit wire, a resistance coil mounted on said switch member and forming a second communication path, a second contact member attached to said first contact member and arranged to heat and move said switch member from contact with said second contact member, and means for forming electrical communication from an unjoined circuit wire to said first contact member.

3. An device of the class described, a unitary body of insulating material having a socket adapted to receive a lamp, a shell terminal and a central terminal within the socket, a conductor bar connecting the shell and extending through the wall of the socket, an exposed connecting terminal on the bar, a second exposed connecting terminal supported by the body, a conductive bar and central terminal, a conductive bar supported by the bottom wall of the socket, a thermoelectric device supported by the body and positioned to be adapted to control an electric current between said post and said second exposed connecting conductor bar connected to the outer end of said post, and means for connecting a wire of a controlled circuit to said last named conductive bar.

3. In a device of the class described, a conductive body of insulating material having a socket adapted to receive a lamp, a lower terminal and a central terminal which are below a conductor bar connecting the two terminals, a conductor bar in the wall of the socket, and a conductive terminal on the bar, a post extending through the bottom wall of the socket and supporting a conductive terminal, a conductive post connected to the central terminal, supported by the post, a conductor bar in the device electrically connected to the conductive post and to the conductive terminal, and a conductive bar connected to the post, and means for connecting a wire of a connecting circuit to said last named conductor bar.
